UNITED STATES PATENT OFFICE

DANIEL SAFFORD QUINTARD, OF NEW YORK, N. Y.

CURTAIN OR PORTIÈRE HOLDER

Application filed September 22, 1931. Serial No. 564,425.

This invention relates to improvements in draperies, and more particularly to novel means for holding back the ribbons or cords employed with window curtains, portières etc.

In my Patent 1,786,365, dated December 23, 1930, I have disclosed a curtain or portière holder, in which the body of the same is made up of interchangeable units of various patterns or colors, to enable a rosette to be built up of the desired units, and the primary object of the present invention is to improve the curtain or portière holder disclosed in said patent.

Another object of the present invention is to provide a unit consisting of a sheet metal disk having stamped out tongues which are interlocked with an annulus of textile fabric.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is an elevation of the improved holder.

Fig. 2 is a similar view of one of the units of the same.

Fig. 3 is a view like Fig. 2, but taken from the opposite side of the unit.

Fig. 4 is a sectional view of the complete holder and illustrating the manner in which the same is attached to a window frame or the like.

Referring to the drawings, 5 designates a metal post provided at one end with a threaded shank 6 to be screwed into a window frame or the like. The opposite end of the post terminates in a threaded shank 8 which is screwed into the wood backing 9 of a suitable button 10 which forms the front of the rosette. The textile fabric 11 which covers the front of the button may be of any suitable color or pattern to match the particular curtains or portières with which the device is to be used.

Arranged between the button and an abutment surface 12 of the post are the inter-

changeable units 13, each of which is preferably formed of a sheet metal disk 14 that is provided with radial cuts 15 to form tongues 16 at one side of the disk. These tongues are employed for clamping a textile fabric disk 17 to a face of the metal disk, as shown, and an annulus 18 of textile fabric is sewed to the disk 17 by the stitches 19, and of course the part 18 will be of any suitable color or pattern.

It is intended that a dealer will stock with buttons 10 and units of various designs and colors, so that the purchaser may select the type desired, and then can build up a rosette to match particular curtains or the like, in accordance with the plan completely outlined in my above mentioned patent.

From the foregoing it is believed that the construction and use of the invention may be readily understood, and I am aware that changes may be made in the details disclosed, without departing from the spirit of the invention, as expressed in the claims.

What is claimed and desired to be secured by Letters Patent is:

1. A composite rosette for curtain holding purposes, comprising superposed units of different sizes, each unit including a metal member having mounted on the face thereof a textile fabric ring, and a fastening device joining said units together.

2. A composite rosette for curtain holding purposes, comprising superposed units of different sizes, each unit including a metal member having mounted on the face thereof a textile fabric ring, and a fastening device joining said units together, each of the metal members having tongues which clamp its textile fabric ring in position.

3. A composite rosette for curtain holding purposes, comprising superposed units of different sizes, each unit including a metal member having mounted on the face thereof a textile fabric ring, and a fastening device joining said units together, each of said metal members being formed of sheet metal and radially disposed integral tongues which clamp its textile fabric ring to the face of the member.

4. A composite rosette for curtain hold-

ing purposes, comprising superposed units of different sizes, each unit including a metal member having mounted on the face thereof a textile fabric ring, a fastening device joining said units together, and a button secured to the outer end of the fastening device by a threaded connection.

5. A composite rosette for curtain holding purposes, including a sheet metal disk having radially disposed integral tongues, and a textile fabric ring superposed on the disk and having its inner edge clamped to the disk by said tongues.

10 6. A curtain holder or the like, including a post having a threaded shank at one end for attachment to a window frame and the like, a second threaded shank projecting from the opposite end portion of the post, the post having an abutment surface at one end 15 of the last mentioned shank, a button engaging the last mentioned shank, and a rosette unit arranged on the last mentioned shank between the abutment and the button, said unit comprising a sheet metal supporting 20 disk provided with integral tongues, and a textile fabric ring mounted on the disk and secured to the same by said tongues.

25 In testimony whereof, I have signed this specification.

30 DANIEL SAFFORD QUINTARD.
